UNITED STATES PATENT OFFICE.

JACOB WILCOX, OF WASHINGTON TOWNSHIP, FRANKLIN COUNTY, OHIO.

GROUND-ANCHOR.

972,306.

Specification of Letters Patent. Patented Oct. 11, 1910.

Application filed June 2, 1910. Serial No. 564,649.

To all whom it may concern:

Be it known that I, JACOB WILCOX, a citizen of the United States, residing in Washington township, in the county of Franklin 5 and State of Ohio, have invented a certain new and useful Improvement in Ground-Anchors, of which the following is a specification.

This invention relates more particularly 10 to the sort of anchor that can be driven into the ground without preparing a hole for its passage.

The object of the invention is to provide 15 an anchor of improved form adapted to provide a more extended surface to the earth against which it may be pulled in proportion to the ease with which it may be inserted than those heretofore proposed.

The invention is embodied in the instance 20 of it herein shown and described, the features of novelty being pointed out by the claims appended to the description.

In the accompanying drawing—Figure 1 25 is a view in elevation of that side of the anchor containing the wire attaching lug showing also the wire and driving rod applied thereto with portions broken out; Fig. 2 is an edge view of the anchor also showing the wire and driving rod as before mentioned; Fig. 3 is an edge view of the anchor with a piece of wire attached showing the position to which the anchor is turned in the ground with reference to the wire when 30 the latter is drawn up with sufficient force to effect the change of position of the anchor; Fig. 4 is a view of the driving rod designed to be used in connection with the anchor.

In the views the character 5 designates 40 the anchor or blade which is made of a thin piece of steel or other suitable metal having pointed or spear shaped end portions 5^a and 5^b of equal dimensions and like form at the ends. The point 5^a is slightly curved 45 to the side opposite that containing the wire receiving lug. The character 6 designates the said wire-receiving lug said lug being erected on one side of the anchor body and provided with an eye 6^a through which one 50 end of the wire, designated 7, is passed and then twisted about itself. The eye 6^a is best located directly opposite the middle of the side of the anchor and therefore at a point 55 equidistant from the two ends of the anchor so that when the latter assumes in the ground a position at right angles to the

pulled wire the resistance to the pull shall be approximately equal at each side.

The point 5^b is the penetrating end of the anchor and the wire receiving lug is extended toward the point of said end in semi-cone or taper form as seen at 6^b so as to provide shoulders 6^c and 6^d at each side of the lug. The wire receiving lug is also provided with a short upward extension 6^e off- 65 set from the face of the anchor.

8 designates the rod for driving the anchor into the ground. This rod should be sufficiently stout to withstand a hard endwise blow without flexing. The lower end of the 70 rod is bifurcate, as seen at 8^a, to straddle the wire-receiving lug between the anchor and the extension 6^e and contact at the crotch and ends with the lug, as seen in Figs. 1 and 2. The shoulders at 6^c and 6^d are of suffi- 75 cient area at their upper sides to wholly confront the ends of the tangs of the driving rod, hence as the anchor is driven into the ground the earth is pushed aside from said tangs and does not tend to interfere with 80 the contact of the rod with the anchor in that operation. Indeed the lower tapered portion of the lug as shown prepares and clears a passage for the driving tool and the wire and its loop connection with the lug. 85 The upward extension 6^e holds the penetrating end portion of the anchor parallel to the driving rod.

To drive the anchor into the ground the parts are associated as seen in Figs. 1 and 2 90 and proper blows of a hammer or mallet applied to the upper end of the driving rod. When the anchor has been driven to a depth desired the driving rod is withdrawn and the wire drawn upon upward thus causing 95 the anchor to assume a position at right angles to the wire as seen in Fig. 3. In this operation the curved upper pointed end of the anchor controls the direction of movement of the anchor into the position desired 100 and after this has been accomplished the wire can be fixed in tense condition or as may be desired to the structure sought to be braced. The anchor can, of course, be driven into the ground in any direction and depth 105 desired and practicable.

Portions of my invention may be used without others, and variations may be resorted to within the scope of my claims.

What I claim is:

1. An anchor of the kind described consisting of a blade each end of which is

formed as a single spear point, each end being symmetrical in form with and of substantially the same area in plan view as that of the other, and the lower or penetrating end being substantially straight and the upper end being curved, said blade being provided at the side from which said upper end curves with a projecting lug constructed to receive a bifurcate driving tool, 5 said lug having a wire-receiving hole offset from the side of the blade and equally distant from the extremities of the blade.

2. An anchor of the kind described consisting of a blade having at one side a wire receiving lug and a tapered extension below said lug provided with laterally extending shoulders, said lug adapted to receive a driving tool and said shoulders adapted to confront the end of said driving tool, substantially as described. 10

3. An anchor of the kind described con-

sisting of a blade having at one side a wire receiving lug, a tapered extension below said lug provided with laterally extending shoulders and an upwardly extending portion above said lug offset from the blade, 25 said lug adapted to receive a bifurcate driving tool straddling said lug, substantially as described.

4. An anchor of the kind described consisting of a blade having at one side a wire receiving lug provided with an upwardly extending portion above said lug offset from the blade, 30 said lug adapted to receive a bifurcate driving tool straddling said lug between the blade and the said offset upward extension of the lug, substantially as described. 35

JACOB WILCOX.
